Primary Examiner — Jennifer L Watkins

(57) **CLAIM**

We claim the ornamental design for a knee brace, as shown and described.

DESCRIPTION

FIG. 1 is a perspective view of a knee brace showing the design;

FIG. 2 is a front view thereof;

FIG. 3 is a rear view thereof;

FIG. 4 is a left side view thereof; and,

FIG. 5 is a right side view thereof.

The broken lines depict portions of a knee brace and form no part of the claim.
